FIG. 5

UNITED STATES PATENT AND TRADEMARK OFFICE
CERTIFICATE OF CORRECTION

PATENT NO. : Des. 593,220 S
APPLICATION NO. : 29/261306
DATED : May 26, 2009
INVENTOR(S) : Debbie Reed

Page 1 of 1

It is certified that error appears in the above-identified patent and that said Letters Patent is hereby corrected as shown below:

Title page, item [54] and col. 1

The title of the Patent should read:

INTERLOCKING GRID FOR PRODUCING A SOIL STABILIZING
GROUNDDWORK

Signed and Sealed this

Eleventh Day of August, 2009

David J. Kappos
